HAIR GROOMING IMPLEMENT HOLDER

Martin J. Wolff, West Haven, Conn., assignor to Sperry
Rand Corporation, New York, N.Y.

Filed June 15, 1972, Ser. No. 263,335

Term of patent 14 years

Int. Cl. D28—03

U.S. Cl. D86—10 F

FIG. 1 is a front side, top and left end perspective view of a hair grooming implement holder, showing my new design;

FIG. 2 is a rear side elevational view;

FIG. 3 is a right end elevational view;

FIG. 4 is a top plan view;

FIG. 5 is a front side elevational view;

FIG. 6 is a left end elevational view; and

FIG. 7 is a bottom plan view.

I claim:

The ornamental design for a hair grooming implement holder, substantially as shown and described.
